UNITED STATES PATENT OFFICE.

HENRY C. SWAIN, OF NEW YORK, N. Y.

DESIGN FOR A DRESSING-CASE.

SPECIFICATION forming part of Design No. 22,687, dated August 8, 1893.

Application filed July 5, 1893. Serial No. 479,680. Term of patent 7 years.

To all whom it may concern:

Be it known that I, HENRY C. SWAIN, a citizen of the United States, residing at New York, in the county and State of New York, have invented and produced a new and original Design for Dressing-Cases, of which the following is a specification, reference being had to the accompanying drawings, in which—

Figure 1 is a front elevation of a dressing case embodying my design; and Fig. 2 is an end elevation of a portion of the case.

The leading feature of my design is a dressing case, of any desired size and material, having a series of drawers in its lower portion, two series of upper drawers, of less length than said lower drawers, arranged at the end of the case, and pilasters situated on each side of the series of upper drawers.

Referring to the drawings, A designates a series of drawers which is arranged in the

lower portion of the dressing case, and B designates the series of drawers which is arranged above the drawers A, at the ends of the case. On each side of each series of drawers, B, are arranged ornamental pilasters C. The drawers B are of less length than the drawers A in the lower portion of the case and in the space between such upper drawers a mirror may be arranged if desired.

Having thus described my invention, what I claim as new, and desire to secure by Letters Patent, is—

The design for a dressing case, substantially as shown and described.

In testimony wherof I hereunto affix my name in the presence of two witnesses.

HENRY C. SWAIN.
